Primary Examiner — Darlington Ly

(57) **CLAIM**

The ornamental design for an electric motorcycle, as shown and described.

DESCRIPTION

1. Electric motorcycle

1.1 is a front and left side perspective view of an electric motorcycle embodying our new design;

1.2 is a rear and right side perspective view thereof;

1.3 is a left side elevation view thereof;

1.4 is a right side elevation view thereof;

1.5 is a front elevation view thereof;

1.6 is a rear elevation view thereof;

1.7 is a top plan view thereof; and

1.8 is a bottom plan view thereof.

1 Claim, 8 Drawing Sheets
